CLAIM

The ornamental design for a collapsible pallet, as shown and described.

DESCRIPTION

FIG. 1 is a top, front perspective view of a collapsible pallet in accordance with our new design, shown in an extended configuration;

FIG. 2 is a rear elevation view thereof;

FIG. 3 is a front elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a right side elevation view of the collapsible pallet of FIGS. 1-7, shown in a collapsed configuration.

The broken lines depict unclaimed subject matter and form no part of the claimed design.

1 Claim, 8 Drawing Sheets
